REVOLUTION COUNTER CASING

Lyndus E. Harper, Chicago, Ill.

Application October 17, 1946, Serial No. 703,880

2 Claims. (Cl. 235—1)

1

My invention relates to revolution counter casings, and, more particularly, to a sealed, integrally united casing of plastic material.

The plastic material that is, preferably, used for making my improved revolution counter casing is a thermoplastic material, such as "Plexiglas" or "Lucite" or a material having similar properties as "Plexiglas" and "Lucite" and being transparent, or a thermo-setting transparent plastic material may be used.

It is a purpose of my invention to provide a revolution counter casing of the above mentioned character, which is provided with a reading window for reading the numbers on the counter members that, preferably, magnifies the figures and also gathers additional light.

It is particularly a purpose of my invention to provide a casing of the above mentioned character that is sealed together liquid or fluid tight and is not assembled by screws or other holding means.

It is a further purpose of my invention to provide means for obscuring the interior mechanism of the revolution counter from observation from the exterior thereof, by providing some form of obscuring means over the other walls of the revolution counter casing than the window portion thereof. Preferably, this is accomplished by providing some roughening or design on the inner surfaces of the walls whereby the same are rendered opaque or translucent.

One of the important advantages of my invention is that a revolution counter casing can be made in this manner which is extremely low in cost of production and which so mounts the revolution counter mechanism as to provide a low cost of production for the entire revolution counter. While the drawings illustrate a revolution counter that is driven from the right side thereof, my invention contemplates the driving of the revolution counter from either end and in either direction, it, of course, being understood that the counter wheels would have to carry indicia in accordance with the direction of rotation of the shaft so as to add in the proper direction of rotation.

Other objects and advantages of my invention will appear as the description of the drawings proceeds. I desire to have it understood, however, that I do not intend to limit myself to the particular details shown or described, except as defined in the claims.

In the drawings:

Fig. 1 is a perspective view of my improved

revolution counter on a somewhat enlarged scale:

Fig. 2 is a vertical sectional view thereof.

Fig. 3 is a section of the revolution counter casing with the counting mechanism omitted, and

Fig. 4 is a view similar to Fig. 2 of a modification.

Referring in detail to the drawings, my improved revolution counter casing comprises a body portion 5, which has an end wall 6 that is substantially plane and a continuous wall that extends perpendicular to said plane end wall 6 and is integral therewith, the same being molded in one piece with the end wall. Said continuous wall, preferably, comprises a bottom wall 7 that is flat or plane on its bottom face 8 and side-walls that have substantially vertical plane outer faces 9 and a curved top wall portion 10 extending from the one vertical face to a more abruptly curved longitudinally extending rib portion 11 that merges with the one vertical side wall 9. The external shape of the body portion is not of any extreme importance, except that it is desirable to have a flat bottom face 8 thereon so that the revolution counter can be mounted on any suitable support by means of screw-threaded members engaging in the screw-threaded openings 12 extending into the body portion from the lower face thereof and to provide the rib 11.

The inner faces of the continuous wall portion projecting from the end wall 6 are shown as comprising a wall portion having a curved inner face 13 substantially parallel to the outer face of the curved top wall 10, and plane vertical faces 14 extending parallel to the vertical outer faces 9, downwardly from the curved face 13 to concavely curved shoulders 15 defining offsets between the plane faces 14 and plane vertical faces 16, which are connected with the flat inner face 17 of the bottom wall 7 by concave portions 18. The chamber thus defined allows for clearance of the moving parts of the revolution counter, including the counter-wheels 19 and the driving mechanism 20 therefor, the same being of a well-known character. The exact shape of the chamber provided within the housing shown in the drawings may be varied so as to provide the desired clearance for the moving parts of the revolution counter and as nearly as possible uniform wall thickness to obtain economy in production by saving in the amount of material embodied in the body portion of said casing and reducing the curing time of the same in the mold and also obtain more uniform curing thereof. However, the

Fig. 1 is a perspective view of my improved

inner face of the wall portion 13 must extend to provide a curvature at 13' opposite the transversely curved rib 11 so that the curvature of the rib 11 is sharper or of smaller radius than that of the wall portion 13' to thus give a magnifying and light concentrating quality to the transparent wall portion 21 that has the outer surface of the rib 11 as its outer surface and the curved wall portion 13' as its inner surface.

The body portion of the casing thus comprises a hollow body having a continuous wall providing a chamber therein running lengthwise of said body portion and an integral end wall at one end thereof. To complete the integrally united transparent fluid tight sealed casing the end wall member 22 is provided, which is made of the same transparent plastic material as the body portion 5. Said end wall 22, preferably, has a projection 23 thereon on one face thereof that is of the shape of the opening in the body portion, as will be obvious from Figs. 2 and 3, the end face 24 of the body portion seating against a shoulder 25 provided between the outer periphery of the member 22 and said projection 23. This provides simple means for aligning the end wall 22 with the body portion 5. The end wall 22 has the same general contour as the outer surface of the body portion 5 and may include a bulge at 26 to align with the transversely curved longitudinally extending rib 11.

The end wall 6 of the body portion 5 is, preferably, provided with a boss 27 integrally molded therewith and the end wall 22 is provided with a similar integrally molded boss 28, said bosses 27 and 28 aligning with each other when the parts are assembled as shown in the drawings. Also each of said end walls 6 and 22 are provided with aligning bearing recesses 29 and 30 in which bearings 31 are provided for the drive shaft 32, a bore 33 of smaller diameter being also provided in the end wall 6 loosely receiving the end portion of the shaft 32 that extends beyond the bearing 31 mounted in the bearing opening 29 and a bore 34 is provided for the drive shaft extending through the wall 22 from the recess 35 smaller than the bearing recess 30, in which is mounted a suitable packing ring 36 that is of a character to provide a liquid or fluid tight seal around the shaft 32, by being clamped between the bearing 31 and the wall of the recess 35.

A counter shaft 37 is provided, upon which the counter members 19 are rotatable, the ends of the shaft 37 being mounted in suitable bearing recesses 38 and 39 provided in the end walls 6 and 22, said bearing recesses 38 and 39 aligning with each other when the parts are in assembled relation.

It will be obvious that when the counter mechanism comprising the counter members 19 mounted on the shaft 37 and the driving means therefor, including the drive members 20 mounted on the drive shaft 32, are mounted within the casing and the wall 22 put in position the parts will be held in assembled position by securing of the end wall 22 in fixed position relative to the body portion 5. Thus the sealing of the end wall 22 to the body portion 5 will seal the counter mechanism within the casing and only the shaft 32 will be accessible from the exterior thereof. It is, of course, to be understood that the counter mechanism is of the usual character and only the gear or driving member 20' is fixed to the shaft 32, the other driving members 20 being freely rotatable on the shaft in the usual manner and each thereof being driven by one

counter member 19 to advance the next counter member the proper proportionate distance upon one revolution of the first mentioned counter member.

The body portion 5 and the end wall member 22 are secured together so as to form an integral sealed liquid tight hollow body or casing either by means of heat and pressure or by the use of a suitable solvent cement, which will integrally unite the adjoining faces of the end wall 22 and the body portion 5 throughout their area of contact.

In order to prevent any confusion in reading the revolution counter and to simplify the reading of the same and at the same time hide the mechanism within the same and thus improve the appearance thereof, means is provided for preventing the observer from seeing through any of the wall portions of the device into the interior thereof, except through the curved magnifying lens or rib portion 11. This may be accomplished in various ways, but preferably, is accomplished by providing a roughening, which may be in the form of any suitable design on the inner faces 13, 14, 15, 16, 17 and 18 of the continuous wall portion and also on the inner faces of the walls 6 and 22, if this is found to be desirable, the roughening being shown in Fig. 1 in perspective as being visible through the transparent portion of said walls and the roughened surface of the curved face 13 of the inner face of the body portion being indicated by the numeral 49, that of the vertical wall 14 by the numeral 41, that of the vertical wall 16 by the numeral 42, and that on the inner face of the end wall 6 by the numeral 43. Said roughening or design that is molded or otherwise provided on said wall portions as above set forth is of such an infinitesimal depth as compared with the size of the parts that it is not possible to show the same in Figs. 2 and 3 except by considerable exaggeration, and has thus been omitted therefrom. The portion 13' of the wall 13 lying opposite the rib portion 11 is not roughened, as will be obvious from Fig. 1 of the drawings.

All of the numerals on the various counter members 19 are not shown in the drawings, only the row of numerals that will lie opposite the magnifying rib or window 11 being shown on the counter members 11 in Fig. 2. These are greatly enlarged by the magnifying wall portion or window 11 in the form of a rib having a much more sharply curved outer wall than inner wall, as will be obvious by comparison of Fig. 1 of the drawings with Fig. 2 thereof. While the scale of Fig. 1 is somewhat enlarged, the difference in the scale is only a small fraction of the difference in size of the numerals as the same appear on the counter wheels and as the same appear through the window 11 as shown in Fig. 1.

Instead of providing an integral end wall on the body portion 5 the body portion may be made as shown in Fig. 4, in which the body portion 5' is shown as being open at the ends, thus forming a barrel-like member of uniform cross section throughout its length, which may be formed by extruding the same and cutting the same into desired lengths. Instead of providing one end wall 22, the end wall 22, which is made in the same manner as previously described, and an end wall 22', which is similar to the end wall 22, are provided. The end wall 22 in the form of the invention shown in Fig. 4 is identical with the end wall 22 shown in Fig. 2, and the same reference numerals are applied thereto.

The end wall 22' is provided with a projection 23', similar to the projection 23 on the end wall 22, being of the shape of the opening in the body portion 5', which is the same as that in the body portion 5. The end face 24' of the body portion 5' opposite the end face 24 seats against a shoulder 25' on the end wall 22' corresponding to the shoulder 25 on the end wall 22. This provides simple means for aligning the end wall 22' with the body portion 5'.

The end wall 22' is also provided with a boss 27, corresponding to the boss 27 of the end wall 6, which aligns with the boss 28 of the end wall 22 when the parts are in the assembled position shown in Fig. 4, and has a bearing recess 29 aligning with the bearing recess 30 in the end wall 22, a bearing 31 being mounted in the recess 29 for the shaft 32. The carrying mechanism shown is the same as that previously described and a bearing recess 38 for the counter shaft 37 is provided in the end wall 22', which aligns with the bearing recess 39 in the end wall 22.

The body portion 5' and the end walls 22' and 22 are secured together in the same manner as is the body portion 5 and the end wall 22 to provide an integrally united fluid tight sealed casing for the revolution counter and is, of course, provided with the window in the body portion in the same manner as in the form of the invention shown in Figs. 1 to 3, inclusive.

In both forms of the invention illustrated the parts that comprise the housing or casing are made of a plastic transparent material which may be either a thermo-plastic or a thermo-setting plastic. If the sections of the casing are made of thermo-plastic material the same may be integrally united by either heat and pressure or by means of a solvent cement. The two thermo-plastics specifically mentioned are methyl methacrylates. Lucite parts may be integrally united by the use of Du Pont cement H-94 or ethylene-dichloride, and Plexiglas parts by means of Rohm and Haas Plexiglas cement No. 1A, or ethylene-dichloride. These plastics and their solvent cements are given only by way of example, as there are numerous other thermo-plastics and thermo-setting plastics commercially available that can be integrally united by means of commercially available solvent cements that have all the essential desirable characteristics required to accomplish the purposes of this invention.

What I claim is:

1. In a revolution counter, a plurality of rotat-

able counter members having indicia thereon and rotating about a common axis, means for rotating the same including a drive shaft, and a sealed integrally united transparent plastic housing for said counter members and said means for rotating the same having a tubular wall portion having an integral rib thereon extending parallel to the axis of rotation of said counter members, said rib having its outer surface curved about an axis parallel to the axis of rotation of said counter members to magnify the indicia on said counter members in alignment therewith, said housing having a bore therein through which said drive shaft extends, and means for providing a fluid tight seal around said shaft in said bore.

2. In a revolution counter, a plurality of rotatable counter members having indicia thereon and rotating about a common axis, means for rotating the same including a drive shaft, and a sealed integrally united transparent plastic housing for said counter members and said means for rotating the same having an integral wall portion having its inner surface curved about the axis of rotation of said counter members and its outer surface curved about an axis parallel to the axis of rotation of said counter members to magnify the indicia on said counter members in alignment therewith, said housing having a bore therein through which said drive shaft extends, and means for providing a fluid tight seal around said shaft in said bore, said housing being provided with means on the inner faces thereof for rendering all the wall portions thereof except said magnifying wall portion opaque.
